UNITED STATES PATENT OFFICE.

ALEXANDER PARKER, OF ETNA MILLS, CALIFORNIA.

DEBRIS OR SEDIMENT COLLECTOR.

1,393,389.

Specification of Letters Patent. Patented Oct. 11, 1921.

Application filed December 16, 1919. Serial No. 345,286.

To all whom it may concern:

Be it known that I, ALEXANDER PARKER, a citizen of the United States, residing at Etna Mills, in the county of Siskiyou and

5 State of California, have invented new and useful Improvements in Debris or Sediment Collectors, of which the following is a specification.

The object of the invention is to provide 10 a device whereby the sediment and filth which accumulates adjacent to dams used in reservoirs and in connection with rivers and streams may be removed for use as fertilizer, particularly in connection with water 15 for irrigation purposes derived from the overflow of such dam, and utilizing the power of the water passing thereover as a means of removing the sediment and accumulations from the bottom of the river or 20 stream adjacent to the upper surface or upstream side of the dam.

With these and related objects in view 25 the invention consists in a construction and combination of parts of which a preferred embodiment is shown in the drawings, wherein:

Figure 1 is a sectional view of the apparatus applied in the operative position.

Fig. 2 is an elevation viewing a dam from 30 the upstream side and showing the apparatus in position therein.

In connection with a dam indicated at 10 and which obviously may be of any preferred construction, wherein the overflow of 35 the reservoir or stream is at the upper edge thereof, a suction pipe 11 is arranged and disposed a short distance below the plane of

the overflow so as to be in the path of water leaving the overflow and provided on the upstream or inner side of the plane of the 40 dam. A plurality of feeder branches 12 which extend approximately to the bottom of the dam, the lever of the water course or reservoir bottom with inlet extremities turned somewhat away from the plane of 45 the dam or upstream so that the suction produced at the outlet end of the pipe 11 serves to draw sediment, filth and collections of vegetable matter, etc., into the feed pipes so that when the overflow water used for 50 irrigation purposes will also carry with it a fertilizing agency which can be used to a distinct advantage in connection with land to be used for agricultural purposes.

The use of a device of this kind obviously 55 will avoid the necessity of occasionally cleaning out the deposit above the plane of the dam or other obstruction and at the same time will provide for the utilization of an otherwise waste material.

What is claimed is:

The combination of a dam, a suction outlet pipe having its end projecting into the water overflowing said dam, a plurality of downwardly extending feeder pipes having their 65 corresponding upper extremities communicating with one end of said suction pipe, said feeder pipes with their inlet ends arranged to the plane of the water course said ends arranged to receive and conduct sediment to said outlet pipe.

In testimony whereof I affix my signature.

ALEXANDER PARKER.
